MATCH PACKAGE

Nathan Hammer, New York, N. Y.

Application February 3, 1943, Serial No. 474,563

1 Claim. (Cl. 206—29)

My invention relates to matches, and has among its objects and advantages the provision of an improved match package of the type which may be carried in the pocket.

An object of my invention is to provide a match package of relatively small proportions and so designed as to contain a relatively large number of matches, together with means affording protection for the matches in the package when a match is struck on the abrasive.

In the accompanying drawing:

Figure 1 is a face view of the match package in its closed condition.

Figure 2 is a similar view with the package opened for the withdrawal of a match.

Figure 3 is a view illustrating the reverse face of the package.

Figure 4 is a view of one group of matches separated from its protective enclosure.

Figure 5 is a sectional view along the line 5—5 of Figure 3, and

Figure 6 is an edge view of the package conditioned in accordance with Figure 2.

In the embodiment of the invention selected for illustration, the package 10 comprises two circular cardboard disks 12 and 14 of the same diameters. Between the disks 12 and 14 are positioned two match disks 16. These disks are of the same diameters and lie face to face between the disks 12 and 14, although the match disks are of smaller diameters so that the two match disks are substantially enclosed inside the cover comprising the two outside disks.

Figure 4 illustrates a face view of one of the match disks 16, and both disks are of light construction. The match disk comprises paper of the type employed in paper matches and is divided by equally spaced radial lines of cut 18 to provide the individual match sticks 20. The cuts 18 terminate short of the axis of the disk 16 to provide a central uncut area 22 provided with an opening 24.

At least one face of the disk 16 may be colored or designed to simulate faces 26 on the individual match sticks, the heads of the matches being indicated at 28 at the outer ends thereof to simulate headdress such as caps. The faces 26 lie adjacent the heads 28, and the remaining areas of the match sticks are colored to indicate uniformed bodies 30, with each match stick having a radial line 32 so that the inner ends of the match sticks simulate leg contours. The different areas on the match sticks may be appropriately colored

with respect to contrast. Thus the match sticks simulate figures.

The match sticks are relatively wide at their outer ends, which provides sufficient material for burning purposes, so that the match sticks may be limited with respect to length. The tapered contour of the match sticks narrows their inner ends so that the individual sticks may be easily torn from the uncut area 22.

10 The cover disk 12 is cut at 34 along a line corresponding substantially to the perimeter of the uncut area 22, which cut runs into a radial cut 36 extending through the perimeter of the disk 12 to provide a flap 38 which may be bent upwardly about a radial scored line 40 to provide an opening 42 lending access to one match stick 20 at a time. The outer face of the flap 38 is provided with the usual striking abrasive 44. Thus the flap 38 must be closed before the match can be struck thereon, thereby affording protection for the matches remaining between the cover disks 12 and 14.

The cover disks 12 and 14 are also provided with central openings arranged coaxially with the openings 24 for the reception of a tubular rivet 46. A staple 48 fixedly connects the two match disks 16 with the cover disk 14, but the cover disk 12 is rotatably supported on the rivet 46 so that the disk 12 may be rotated from match to match.

Without further elaboration, the foregoing will so fully explain my invention, that others may, by applying current knowledge, readily adapt the same for use under various conditions of service.

I claim:

35 In a match package, a pivot element, a pair of complementary front and rear cover disks of corresponding diameter, said disks being concentrically mounted to turn about said pivot, a match disk concentrically mounted on said pivot between and parallel with said cover disks, said match disk being of smaller diameter than the cover disks and slotted radially inward from its peripheral edge to form match sticks, the outer ends of the match sticks having striking heads, said front cover having a slit extending radially inward from its peripheral edge to a point short of its center with its inner end opening into a circumferential slit, said slits in conjunction with a radial fold line defining a flap which is adapted to swing outward along the fold line to provide an opening slightly wider than each match for individual removal of said matches.

NATHAN HAMMER.
